United States Patent Office.

OLE K. BERNBAUM, OF BROOKLYN, NEW YORK.

Letters Patent No. 71,956, dated December 10, 1867.

IMPROVED FOLDING TRUNK.

The Schedule referred to in these Letters Patent and making part of the same.

TO ALL WHOM IT MAY CONCERN:

Be it known that I, OLE K. BERNBAUM, of Brooklyn, Kings county, New York, have invented, made, and applied to use a new and useful Folding Trunk; and I do declare the following to be a full, clear, and correct description of my said invention, reference being had to the accompanying drawings, making part of this specification, and to the letters of reference marked thereon, in which—

Figure 1 is a transverse sectional view of my improved trunk when in use.

Figure 2, a longitudinal sectional view of my improved trunk when in use.

Figure 3, a transverse sectional view of my improved trunk, showing the same when being folded.

In the drawings, like parts of the invention are pointed out by the same letters of reference.

The nature of my invention consists in the construction and operation of a folding trunk, as more fully hereinafter set forth.

The object of the present invention is to so construct a trunk that, when not in use, it may be folded up, and thus be made to occupy less room than if made in the ordinary way. To sailors, travellers, and others, my invention will be found particularly valuable.

To enable those skilled in the arts to make and use my invention, I will proceed to describe the same.

The frame of my trunk may be made of wood, metal, or any suitable substance, the front portion of the same consisting of two parts or pieces, *a*, hinged together about midway the height of the trunk when ready to be packed. The back portion of the same is also made of two parts or pieces, *b*, hinged together in the same manner. The ends of the trunk, shown as *B* and *C* upon the drawings, are hinged at the bottom of the trunk, and made so as to fold inward, as shown in fig. 2, when it is desired to fold the trunk up, and outward and beneath the top of the frame when it is desired to use the trunk. The framework being thus made may be covered externally and internally, as desired, or as may be deemed necessary.

Such being the construction, the operation is as follows: When in use, the trunk presents the appearance shown in fig. 1 of the drawings, the ends of the trunk being thrown outward and beneath the top of the frame, and thus keeping the front and back portions of the same in an upright position. When not in use, the trunk may be folded or closed, by folding inward the ends *B* and *C*, which no longer supporting the hinged back and front, the same gradually fold or fall downward and inward, as is clearly shown in fig. 3, greatly reducing the size of the trunk, and rendering it capable of being stowed away within a comparatively small compass.

As before stated, for sailors, travellers, and all using trunks, and desirous that the same should occupy much less room than trunks usually do, my invention will be found particularly valuable.

Having thus described my invention, what I claim as new, and desire to secure by Letters Patent, is—

The folding ends, in combination with the hinged sectional back and front, for the purposes herein fully described.

OLE K. BERNBAUM.
